FIG. 10.

UNITED STATES PATENT OFFICE.

ISRAEL BENJAMINS, OF BROOKLYN, NEW YORK.

BELT BUCKLE.

1,407,185.

Specification of Letters Patent. Patented Feb. 21, 1922.

Application filed April 30, 1921. Serial No. 465,884.

To all whom it may concern:

Be it known that I, ISRAEL BENJAMINS, a citizen of the United States, residing at Brooklyn, in the county of Kings and State 5 of New York, have invented a new and useful Belt Buckle, of which the following is a specification.

My invention consists in the novel features hereinafter more fully described, and the 10 objects of my improvement are:

First: to produce a belt buckle, which is not slotted nor perforated on the front thereof;

Second: to produce a buckle, which is comparatively free from slots and perforations on the rear thereof, except where 15 connected to the belt;

Third: to have said belt buckle easy to open and easy to close; and

Fourth: to have said belt buckle simple, 20 durable and inexpensive.

I attain these objects by the belt buckle illustrated in the accompanying drawings or by any mechanical equivalent or obvious modification of the same.

25 The accompanying drawings are made to a larger scale for the sake of clearness.

In the drawings Fig. 1 is a vertical section on the line 1—1 of Fig. 2, looking towards the left; Fig. 2 is a vertical section on the 30 line 2—2 of Fig. 1, looking towards the right; Fig. 3 is a vertical section on the line 3—3 of Fig. 1 looking towards the left; Fig. 4 is a horizontal section on the line 4—4 of Fig. 1.

35 Fig. 5 is a rear elevation of one form of my belt buckle, showing the slots for connecting the buckle to a cloth belt.

Fig. 6 is a plan of the right half or hand piece of my belt buckle; Fig. 7 is a plan of 40 the left half or socket piece of my belt buckle.

Fig. 8 is a front elevation of the form of my belt buckle, shown in Fig. 5, and Fig. 9 is a horizontal section of the socket piece 45 of my belt-buckle, showing a connection to the end of a leather belt.

Fig. 10 is an elevation of one form of the spring and lever of my belt buckle showing them as made in one piece with the projection or catch soldered thereto.

Similar numerals refer to similar parts throughout the several views.

11 designates the hand piece and 12 the socket piece of my belt buckle, which are 55 shown in Figs. 2 and 3 as having each its

front and rear made of one piece of metal bent over at the middle thereof, thereby forming the top edge of the piece.

It is evident from Fig. 4 that the front of the hand piece 11 is substantially continuous 60 with the front of the socket piece 12, both together forming the front of the belt buckle.

The bottom or lower edge of the socket piece is formed by the strips 12^b and 12^a, which 65 may be soldered to the lower edges of the front 12^e and rear 12^r of the socket piece leaving the opening 17 between the adjacent ends of said strips 12^a and 12^b.

The strip 12^a is shown as tapered to permit 70 the projection or catch 14 of the spring 13 readily to pass thereover.

Said spring 13 may be made of a bar or strip of metal bent into the shape as shown in Fig. 1 or into some similar shape, and it 75 may have its upper branch soldered or otherwise connected to the top edge of the hand piece 11, preferably inside thereof; the lower branch of said spring 13 is shown in Fig. 1 as terminating in the projection or catch 14, 80 and it has the lever 15 soldered or otherwise connected thereto; said lever 15 terminates in the handle 16.

It is evident that by inserting the bend of the spring 13 into the socket piece of my 85 belt buckle and then moving the hand piece and socket piece thereof towards each other, the projection or catch 14 will enter the opening 17, above described, and the buckle will thereby be locked.

The action of the spring 13 is in a plane substantially parallel to the front of the belt-buckle, as is evident from Fig. 1.

To unlock the buckle, the handle 16 of the lever 15 is pressed upward towards the top 95 of the buckle, whereby the projection or catch 14 is lifted out of the opening 17, and the hand piece may then be separated from the socket piece.

To facilitate the pressing of the handle 16 100 upwardly I provide a cutout in the lower edge of the front 11^f and also one in the rear 11^r of the hand piece of about the same size as said handle 16 and opposite thereto.

To make the appearance of the buckle symmetrical I provide the groove 20 in each of the front 12^e and rear 12^r of the socket piece of about the same size and shape as said cutouts in the hand piece and symmetrical thereto, as shown in Figs. 5 and 8.

18 and 19 are slots, shown in Fig. 5 in the rear of my belt buckle at each end thereof, for connecting the same to the ends of a cloth belt.

5. To connect my buckle to a leather belt I propose to have a set of teeth 23 in each end of the rear 22^r of the form of my buckle, the socket piece of which is shown in Fig. 7; the edge adjacent to the set of teeth may be 10 initially bent as shown; the end of the belt 24 is then inserted between said teeth 23 and the opposite edge of the front 22^f of my buckle, when said end 24 may be secured in place by still further bending the edge with 15 the teeth 23 inwardly.

13^a is another form of the spring of my belt buckle shown in Fig. 10 as made in one with the lever 15^a and handle 16^a; the projection or catch 14^a may be soldered or otherwise connected to said lever 15^a, and it is 20 shown as rounded off on the bottom and side thereof opposite the socket piece to facilitate its passing over the strip 12^a of the socket piece and into the opening 17 thereof.

25. The handle 16^a terminates in the bead 16^b, which may extend beyond the end of the hand piece 11 of my belt buckle, when assembled, to facilitate the pressing of the handle 15^a upwardly, in which case no cut out is 30 necessary in the front and rear of the hand piece of my belt buckle, nor any groove 20 in the socket piece thereof, as hereinbefore described.

Many other changes could be made in the 35 details of my belt buckle without departing from the main scope of my invention.

I do not, therefore, restrict myself to the details as shown in the drawings; but I intend to include also all mechanical equivalents and reasonably obvious modifications 40 of the same within the scope of my invention.

What I claim as my invention, and desire to secure by Letters Patent is:

45. 1. In a belt buckle a socket-piece and a hand-piece, each of said pieces having a front, which is a continuation of the front of the other piece, combined with a U-shaped

spring situated in and adapted to act in a plane substantially parallel to the front of 50 the buckle, said spring being connected to the hand piece and adapted to be detachably interlocked with said socket piece.

2. In a belt buckle a socket piece having two edges thereon, a hand piece and a U- 55 shaped spring connected to said hand piece and adapted to be interlocked with said socket piece, the two prongs of the spring being in continuous contact with said edges through a considerable part of their lengths, 60 when the buckle is closed, thereby insuring the correct position of said hand piece with relation to said socket piece.

3. In a belt buckle a socket piece and a hand piece, each made of a strip of sheet 65 metal bent to shape, and each having thereon an edge and a front, which is a continuation of the front of the other piece, combined with a U-shaped spring situated in and adapted to act in a plane substantially parallel to the front of the buckle, said spring being connected to the edge of said hand piece and adapted to be detachably interlocked with the edge of the socket piece. 70

4. In a belt buckle a socket piece and a 75 hand piece, each having therein a rear, an edge and a front made of a strip of sheet metal bent to shape, the fronts of the two pieces being substantially continuous, combined with a U-shaped spring, situated between said rears and said fronts, and adapted to act in a plane substantially parallel thereto, said spring being connected to the edge of said hand piece and adapted to be detachably interlocked with the edge of said 80 socket piece.

5. In a belt buckle a hand piece and a socket piece having a lower edge thereon, combined with a U-shaped spring connected to said hand piece and adapted to be interlocked with the lower edge of said socket piece, and each of said pieces having a front, which is substantially continuous with the front of the other piece. 90

ISRAEL BENJAMINS.
